UNITED STATES PATENT OFFICE.

EMIL BOMMER, OF BROOKLYN, NEW YORK.

ADVERTISING-CARD.

SPECIFICATION forming part of Letters Patent No. 247,601, dated September 27, 1881.

Application filed February 18, 1881. (Model.)

To all whom it may concern:

Be it known that I, EMIL BOMMER, of the city of Brooklyn, in the county of Kings and State of New York, have invented certain new and useful Improvements in Advertising-Cards, of which the following is a specification.

This invention has reference to improvements in devices and means for displaying advertisements, business-cards, and the like in such a manner that little or no material is wasted, and that a portion of the device is adapted to be bent back and used as a support or rest for the card in upright or inclined position, which portion, however, forms a part of the card when placed flat in line with the body of the card.

The invention consists of a card the body of which is provided with cuts or incisions running parallel to the sides of the same at two adjoining corners thereof, the cuts or incisions being continued to points near the opposite corners and to points midway between two adjoining corners, so that the cut-off portions, when bent back, form supports or braces for the card.

A locking-tongue cut out from one of the rests may be inserted through a slit of the other rest, so as to form a locking device for the rests or braces when in bent-back position.

In the accompanying drawings, Figures 1 and 3 represent perspective views of my improved advertising-card, shown in position as supported by the rests or braces bent back from the body of the same; and Figs. 2 and 4 are plan views of the card, shown with the rests or braces flat in one plane with the card, for being carried in the pocket or packed for shipment.

Similar letters of reference indicate corresponding parts.

In the drawings, A denotes a business or other advertising card, of any suitable size or shape and thickness, the body of which is provided, along three sides thereof, with cuts or incisions B, which extend from points near the center of one side of the card, around two adjoining corners, to points at or near the remaining corners, as shown clearly in Figs. 2 and 4. By 45 these cuts or incisions B, arranged, as de-

scribed, around two adjoining corners of the card A, there are separated from the body of the card two angular portions, C, which, when bent back at a suitable inclination to the body of the card, form rests or braces for the same. 55

The points at which the angular rests or braces C are bent back from the body A may be creased or indented, so as to facilitate the bending back, as shown in dotted lines at x in Figs. 2 and 4. When the rests or braces 60 are bent back so as to be sidewise of each other they may be locked together by a tongue, D, cut in one brace, which is passed through a transverse slit, E, of the other brace, as shown clearly in Figs. 1 and 2. This locking 65 together of the rests or braces by a tie is especially advantageous in larger-sized cards, so as to give a firm support thereto.

The advantages of my improved advertising-card are that the braces and body of the 70 card are in one plane sidewise of each other when not bent back, so that they can be carried in the pocket and answer all the purposes of an ordinary business-card, while the rests or braces may at any time be bent back so as 75 to form a support for the business-card and bring out the matter thereon in a more prominent and effective manner.

I am aware that advertising devices with single braces, which are cut out from a continuous piece of paper, have been used heretofore and are well known, and I therefore do not claim the same, broadly. In these cases the rests or braces do not form a part of the body of the card or advertising device itself 85 when used in a flat condition as a business-card, which forms the essential novel feature of my device.

Having thus described my invention, I claim as new and desire to secure by Letters Patent— 90

1. A business-card provided with two angular rests or braces formed by cuts or incisions at two adjoining corners of the card, said rests or braces being bent back at points midway between the adjoining corners and at points 95 near the opposite corners of the card, substantially as and for the purpose set forth.

2. A business-card provided with rests or braces which are formed by cuts or incisions at two adjoining corners, said rests being bent 100

back at points midway between the adjoining corners and near the opposite corners, and connected by a suitable locking device when bent back, substantially as specified.

5 3. A business-card having angular rests or braces formed by cuts or incisions extending around two adjoining corners of the card, said rests or braces forming a portion of the card

when laid flat therewith, or supporting braces when bent back to a suitable inclination thereto, substantially as described.

EMIL BOMMER.
